UNITED STATES PATENT OFFICE.

IRVING G. CHATFIELD, OF WATERBURY, CONNECTICUT.

DETACHABLE FIRE-BOX FOR COOK-STOVES.

SPECIFICATION forming part of Letters Patent No. 727,090, dated May 5, 1903.

Application filed November 24, 1902. Serial No. 132,552. (No model.)

To all whom it may concern:

Be it known that I, IRVING G. CHATFIELD, a citizen of the United States, and a resident of Waterbury, in the county of New Haven and State of Connecticut, have invented certain new and useful Improvements in Detachable Fire-Boxes for Cook-Stoves, of which the following is a specification.

My invention relates to new and useful improvements in detachable fire-boxes for cook-stoves, the same being particularly adapted for burning charcoal, soft coal, and the like. It is the object of the invention to construct an inexpensive sub fire-box which has a contracted lower portion to fit in the regular fire-box of an ordinary cook stove or range by simply removing the two front lids and cross-bar therefrom and seating the box in the opening therefor. Further, to so arrange the fire-box that the covers removed from the stove can be utilized for covering the box, thus having the stove present substantially its original appearance. Finally, to provide openings in one side of the pot and a shield or guard for the fire-box adjacent to said opening to insure the draft for the stove passing through the fire-box and its fire as desired.

With the above objects in view my invention resides and consists in the novel construction and combination of parts shown upon the accompanying drawings, forming a part of this specification, upon which similar letters of reference denote like or corresponding parts throughout the several figures, and of which—

Figure 1 shows a plan view of my improved fire-box complete. Fig. 2 is a side elevation, partly broken away, illustrating the box partially in a central vertical longitudinal section. Fig. 3 is a transverse cross-section taken in line 3 3 of Fig. 2, the same more clearly illustrating the offsets or shoulder formed on the fire-box, together with the shield for controlling the draft.

As will be apparent from the illustration, my fire-box consists practically of two pieces, one being a casting, which is light and can be produced from stove-iron inexpensively with comparatively little fitting and finishing, the other part a shield, which may be

formed of sheet metal secured to the rear of the box.

Referring in detail to the characters of reference marked upon the drawings, A represents the fire-box as a whole, and B the shield.

c indicates the top rim of the fire-box, and d the end extensions thereof, having lifting-holes e formed therein.

f represents an external shoulder which in practice rests on the edge of the hole in the top of the stove. The body of the fire-box below this shoulder is of a size corresponding to that of the opening formed for the covers, which obviously insures the fire-box resting snugly within the fire-box of the stove and central thereof. A series of transverse openings h are formed in the bottom of the fire-box, thus producing grate-bars i, upon which the bed of the fire rests in the usual way, the ashes from which can be worked down with a poker, brush, or small broom, as is the custom with a charcoal fire.

On the rear side of the grate I form a series of openings j, through which the products of combustion pass out into the top of the stove and thence off through the smoke-passage of the same in the customary way. Upon the same side of the grate and adjacent to these openings is located an external shield B. The bottom k of this shield in practice rests upon the top of the oven portion of the stove, and the ends l of the shield close the space between the end of the grate and the sides of the stove intermediate of the ends of the grate and the space formed over the top of the oven, thus avoiding any draft around the box, but insuring such draft passing through the box and out of the openings j referred to.

On the inner edge of the top rim c of the grate I form an annular recess m to receive the three front covers indicated in dotted lines in Fig. 1, which, as before intimated, would be the same covers that were taken from the stove for the reception of the grate, thus making it possible to use the stove in the same way with this grate and a charcoal fire as would be with the ordinary grate and coal fire.

From the foregoing it will be seen that I arrange the fire-box so as to form a compartment which will not be so deep as that ordinarily found in cook-stoves, thus providing a

shallow fire nearer the surface than it would be if the fire were built in the ordinary deep fire-box of stoves of this class. It is further true that owing to the peculiar nature of charcoal a fire can be used in one end of the grate only more economically than a coal fire could be used in the ordinary coal-grate. This could be used with or without a transverse partition. Should the latter be desirable, it could be formed of any suitable piece of metal and inserted through one of the transverse openings between the grate-bars, as indicated by *n* in Fig. 2.

Having thus described my invention, what I claim, and desire to secure by Letters Patent, is—

1. A detachable fire-box for cooking-stoves, the same comprising a top formed of a single piece having a grated bottom and of a shape and size to fit into the stove-opening, and having openings in the rear side of the pot, a shield secured to said side, the same adapted

to form an inclosed passage from the box to the top flue of the stove, thus insuring a draft through said fire-box, substantially as described. 25

2. A fire-box comprising a body having an annular rim, a recess formed on the inner edge of said rim to receive the stove-covers, a contracted lower portion to said fire-box, with transverse grate-bars forming the bottom proper and openings through the side of the fire-box, a shield comprising a bottom and end portion to constitute a flue for said fire-box and to deflect the products of combustion 30 into the flue-channel of the stove, substantially as described. 35

Signed at Bridgeport, in the county of Fairfield and State of Connecticut, this 30th day of October, A. D. 1902.

IRVING G. CHATFIELD.
